CLAIM

The ornamental design for a working lamp, as shown and described.

DESCRIPTION

FIG. 1 is a perspective view of a working lamp, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a view of bent state thereof; and,

FIG. 9 is another view of bent state thereof.

In the drawings, the broken lines show portions of the working lamp that form no part of the claimed design.

1 Claim, 9 Drawing Sheets(56)
